UNITED STATES PATENT OFFICE.

LUTHER D. LOVEKIN, OF PHILADELPHIA, PENNSYLVANIA.

STEAM-GENERATING BOILER.

1,128,700.

Specification of Letters Patent. Patented Feb. 16, 1915.

Application filed February 6, 1912. Serial No. 675,792.

To all whom it may concern:

Be it known that I, LUTHER D. LOVEKIN, a citizen of the United States of America, residing in the city and county of Philadelphia, in the State of Pennsylvania, have invented a certain new and useful Improvement in Steam-Generating Boilers, of which the following is a true and exact description, reference being had to the accompanying drawings, which form a part thereof:

My present invention consists in an improved steam generating boiler of the water tube type especially adapted for oil firing and suitable for marine service.

15 The primary object of the invention is to provide a simple and effective boiler construction for the purpose specified characterized by the provisions made for obtaining a large combustion space and for regulating 20 the circulation of the hot gases through the groups of boiler tubes.

25 The various features of novelty which characterize my invention are pointed out with particularity in the claims annexed to and forming a part of this specification. For a better understanding of the invention, however, and the advantages possessed by it, reference should be had to the accompanying drawings and descriptive matter in 30 which I have illustrated and described a preferred form in which my invention may be embodied.

35 Of the drawings, Figure 1 is a front elevation of a marine boiler constructed in accordance with my invention with the oil burners and provisions for regulating the admission of air to the combustion space removed. Fig. 2 is an elevation of a portion of the water tubes and the provisions employed in conjunction therewith to provide 40 a baffle for the hot gases. Fig. 3 is a section on the line 3—3 of Fig. 2. Fig. 4 is a sectional elevation taken on the line 4—4 of Fig. 1, with a portion of the boiler broken 45 away. Fig. 5 is a partial sectional elevation on the line 5—5 of Fig. 4.

50 The boiler construction shown by the drawings comprises an upper horizontal steam and water drum A and a lower pair of horizontal water drums B, B, parallel to the drum A and disposed at opposite sides thereof. The return connections C and C' connect the front end of the drum A to the front ends of the drums B, B, and the rear 55 ends of these drums are similarly connected by the return connections D and D'. Each

drum B is also connected to the drum A by a corresponding set or group of curved water tubes E. The boiler housing F is suitably lined and covered with heat insulating material, indicated at F' and F², and encloses the two groups of water tubes C and the major portion of the steam and water drums A. The water drums B, B, have their body portions embodied in the housing wall, 60 the portion of these drums extending beyond the housing proper being covered with suitable heat insulating material F³. The return connections C and C' and D and D' lie beyond the end walls of the housing 65 proper as do the ends of the drums A and B, B, between which these connections extend. The front end of the boiler housing is provided in its upper portion with a series of suitably disposed cleaning doors F⁴ opening 70 into the upper portion of the combustion space, and openings F⁵ for the oil burners are formed in the front end wall of the housing in front of the combustion space G. Inasmuch as the character of the oil burners 75 proper forms no part of the present invention I have not illustrated the specific construction of these parts which are not shown at all in Fig. 1, although the oil burners J are shown in outline in Fig. 4. A metal 80 wall K in front of the boiler below and between the return pipes C' C' forms the outer wall of an air chamber surrounding the burners J, and doors K' are provided to control the admission of air into this air 85 chamber.

90 The tubes E extend substantially vertically for some distance above the drums B and then curve in toward the drum. This arrangement provides a combustion space G 95 of large volume which is especially desirable for oil firing. To confine the hot gases and prevent them from passing in appreciable amount directly into the lower portions of the groups of tubes E, I provide baffles H, 100 H, at the inner side of each tube group E adjacent the lower ends of the tubes. As shown, the baffles H are formed of bricks h, each of a width on the side adjacent the combustion chamber slightly less than one half the distance between the centers of the adjacent tubes in the inner row. Each of the bricks is formed with a rounded channel h³ adapted to snugly receive a portion 105 of one of the tubes E. In the assembled 110 baffle each brick is locked in place between one of the tubes E and the brick h engaging

the adjacent tube. The bricks are shaped to provide a slight air gap h' between the inner sides of the two opposing bricks at the opposite sides of a single tube E, and a 5 somewhat larger air gap h^2 at the outer side of the baffle. The lower edges of the baffles H are slightly above the lower ends of the inner rows of tubes E.

As shown, the inner rows of tubes are 10 formed with reversely curved portions E' which give increased thickness to the groups of tubes. As shown the curvature of these portions E is sufficiently sharp to prevent the baffle bricks h from sliding down on the 15 supporting tubes below the position occupied by them in the drawings. To cause the hot gases entering the groups of tubes E above the baffles H from passing directly to the passages G' between the boiler housing 20 and the outer tubes E, baffles I are placed on the outer sides of the two tube groups extending from the drum A nearly to the level of the tops of the baffles H. A hood I' extends from the tops of the baffles I about the 25 upper half of the drum A and shields the latter from direct contact with the partially cooled waste gases passing through the channels G' to the outlet passage G². By preference the upper ends of the tubes 30 in each group are spread apart as shown to provide an intertube space diminishing in cross-section from the steam and water drum A along the tubes approximately to the plane connecting the top edge of baffle 35 H and the bottom edge of the baffle I. With the arrangement of water tubes and baffles described the bulk of the highly heated gases passing out of the large combustion space G proper, enters the intertube space 40 above the baffles H and then passes across and down along the tubes E to the outlet channel G'. The path of the hot gases is indicated by the arrows in Fig. 5. As the hot gases pass into and down from the upper end of the intertube space in each group 45 of tubes E, the volume of the gases diminish as they impart their heat to the tubes E, and the similar decrease in volume of the intertube space, as the distance from the steam and water drum A increases, gives a desirable 50 uniformity in the speed with which the hot gases pass through the intertube space. With the circulation described, the flow of hot gases along the tubes E is for the most part downward and counter to the direction of flow of the ascending water in the tubes E so that the upper ends of the tubes E are heated to a higher temperature than are the lower ends, as is desirable. The fact that 55 the lower edges of the baffles H terminate some distance short of the drums B permits of a flow of hot gas from the combustion chamber into the lower ends of the intertube spaces, which, while restricted, is sufficient 60 to apply the proper amount of heat to the 65

lower end of the tubes E. The gap between the lower edge of each baffle H and the adjacent water drum serves to restrict the accumulation of soot in the lower ends of the inter tube spaces, since soot may fall 70 through the gap into the combustion space, and moreover the current of hot gas passing through this gap tends to carry the finer soot particles along with it. With the construction described it is apparent that the 75 water circulation through the tubes E will be upward from the drums B to the drums A, and an adequate return flow of water from the drum A to the drums B is insured by the large and unheated return connections C and C' and D and D'.

While in accordance with the provisions of the statutes I have illustrated and described the best form of my invention now known to me, it will be apparent to those skilled in the art that changes may be made in the forms of the apparatus disclosed without departing from the spirit of my invention, and that under some conditions certain features of my invention may be used 85 with advantage without a corresponding use of other features.

Having now described my invention what I claim as new and desire to secure by Letters Patent is:

1. A boiler comprising a pair of spaced apart water drums and a steam and water drum located above and between the water drums, two outwardly bowed groups of water tubes, one connecting one and the other the second of said water drums to the steam and water drum and uniting to form the top wall of a combustion chamber, return connections between the ends of the steam and water drum and the ends of the water drums, a baffle arranged along the lower portion of the inner side of each group of water tubes, the lower edge of said baffle being somewhat spaced away from the adjacent water drum, a baffle arranged along the upper portion of the outer side of each group of water tubes whereby a relative large portion of the hot gases from the combustion chamber is caused to enter the spaces between the tubes in each group adjacent the upper end of the latter and then pass down by the second mentioned baffle, and a relatively small portion of the hot gases is caused to enter the spaces between the tubes in each group adjacent the lower end of the tubes, the tubes in each group being spread apart adjacent their upper ends whereby the volume of intertube space in each group diminishes as the distance from the steam and water drum increases.

2. A boiler comprising a pair of spaced apart water drums and a steam and water drum located above and between the water drums, two outwardly bowed groups of

water tubes, one connecting one and the other the second of said water drums to the steam and water drum and uniting to form the top wall of a combustion chamber, re-
5 turn connections between the ends of the steam and water drum and the ends of the water drums, a baffle arranged along the lower portions of the inner side of each group of water tubes, and a baffle arranged
10 along the upper portion of the outer side of each group of water tubes whereby the hot gases from the combustion chamber are caused to enter the spaces between the tubes in each group adjacent the upper end of the latter and then pass down by the second 15 mentioned baffle, the tubes in each group being spread apart adjacent their upper ends whereby the volume of the inter-tube space in each group diminishes as the distance from the steam and water drum increases.

LUTHER D. LOVEKIN.
